LISTING MACHINE

Howard Moffatt Fleming, West Orange, N. J.,
assignor to Monroe Calculating Machine Company, Orange, N. J., a corporation of Delaware

Application March 4, 1939, Serial No. 259,868

4 Claims. (Cl. 197—189)

The invention relates to listing machines having a shiftable paper carriage provided with a rotary platen, suitable line spacing and fractional line spacing means, and a signal bell to give the operator notice when a predetermined point is reached in matter being typed upon a paper sheet passing around the platen.

An object of the invention is to provide means for fractionally adjusting a driven gear forming part of the signaling means operable with means for bodily moving said gear relative to a drive gear fast on the platen shaft so that these gears will mesh in case there shall have been fractional line spacing adjustment of the platen. Other objects and advantages will appear hereinafter.

The invention consists in the novel construction and combinations of parts as hereinafter set forth in the claims.

In the accompanying drawings,

Figure 1 is a plan view of the invention as applied.

Figure 2 is a section on the line 2—2, Figure 4, with bell removed, and gears disengaged.

Figure 3 is a similar view to Figure 2, with gears engaged.

Figure 4 is a longitudinal section through the shaft whereon the signal gear is mounted, parts being broken away.

Figure 5 is a view similar to Figure 2 on a larger scale, showing the manual levers in inoperative position in full lines, and in operative position in dot and dash lines.

Figure 6 is a section on the line 6—6, Figure 4, showing the gears meshed.

In these drawings, the numeral 1 designates the rotary platen of a listing machine, such for instance as disclosed in the U. S. Patent to Crosman No. 1,945,026, issued Jan. 30, 1934, said platen being mounted upon a shiftable carriage 2.

Any suitable line spacing means and fractional line spacing means for the platen may be used. In this case however, the disclosure of the U. S. Patent to Loring P. Crosman, No. 2,134,605, issued October 25, 1938, is followed, wherein there is a main handle knob 3 for line spacing and a secondary handle knob 4 for fractional line spacing or preliminary alignment of the paper sheet.

Broadly old signaling means is used, which may be disabled or rendered operative by moving a spur gear 5 bodily relative to or into and out of mesh with a pinion 6 fast on the platen shaft.

Fast to sleeve 7, mounted for rotary and longitudinal movement upon a shaft 8 whereupon spur gear 5 is rotatably mounted, is radial arm 9, hav-

ing toothed outer end 10 adapted upon inward longitudinal movement of said sleeve to engage predetermined teeth of gear 5 in accord with the rotary setting of radial arm 9, to permit varying rotation of gear 5 for typewritten matter of a varying number of lines, prior to sounding of the signal bell. In this setting, said sleeve 7 is first moved outwardly longitudinally of shaft 8 against the tension of its spring 11 to disengage toothed end 10 from gear 5, the sleeve being then moved rotatably to a new position on gear 5 in accord with the predetermined number of lines to be typed on the paper sheet prior to sounding of the signal, following which rotary movement of the sleeve is released for retractive longitudinal movement and toothed end 10 engaged with other teeth of gear 5.

The shaft 8 is fast with a pivotal arm 13 to be described, and in order to accomplish bodily movement of the gear 5 into and out of mesh with platen gear 6, a manual lever 14, fulcrumed at 15 to the carriage framing has a cam slot 16 engaging a clamp nut 17 to be described and which forms in effect an axially aligned end extension of shaft 8, operation of manual lever 14 moving gear 5 bodily upon the pivot of arm 13 as a center.

Fulcrumed at 17 upon and moving with radial arm 9 is a bell clapper lever 18, having a tooth 19 adapted in one direction of movement of said arm to engage a tooth 20 of pivotal arm 13 to thereby depress said bell clapper lever against the tension of its spring 21, said lever being released after tooth 19 passes tooth 20, to sound the signal bell 23. In the opposite direction of movement of radial arm 9, tooth 19 is adapted to yield and pass tooth 20 without operation of the bell clapper lever. Tooth 19 forms part of a lever 24, fulcrumed at 25 to the bell clapper lever and in clockwise movement of the parts as seen in Figure 5, tooth 20 exerts pressure upon the double beveled tooth 19 in the direction of the length and in line with the fulcrum of lever 24 and both levers 24 and 18 are depressed as a unit, whereas in counter-clockwise movement of the parts, tooth 20 exerts pressure upon tooth 19 at right angles to lever 24 and said lever and its tooth will yield and pass tooth 20 without operation of the bell clapper lever. The retracting spring 21 of clapper lever 18 has connection at one end with stud 22 of radial arm 9, said stud engaging a slot 26 of the lever and acting to limit the movement of the lever in both directions. The lever 24 has its retracting spring 27 attached also to stud 22, and the toothed end portion of said lever has an

angle 30 .
30 .
35 .
40 .
45 .
50 .
55 .

extension 24, engaging under fulcrum 17 to limit the rise of the tooth 19.

Retraction of manual lever 14 moves gear 5 bodily upon the pivot of arm 13 as a center and disengages said gear from the platen gear 6, and this disengagement being effected, a spring 11' to be described and which has the coils thereof wound and tensioned during the rotation of gear 5 in the typing of the matter on the paper sheet, 5 will retract gear 5, sleeve 7 and radial arm 8 as a unit rotatably to first or starting position, a lateral stud 28 of said gear having stop engagement with one end of a lever 29, fulcrumed at 10 to said pivotal arm 13, to limit the movement.

During the reverse movement of the parts, stud 28 is adapted to engage a laterally bent end of and operate lever 29 against the tension of its 15 retracting spring 31 and pass said lever without any such stop, said bent end having normal stop engagement with extension 13' of arm 13.

The following means are provided to fractionally rotate the gear 5 (in case there shall have been fractional line spacing rotation of the platen) at the same time that said gear is moved bodily towards the platen shaft gear 6, so that these gears will mesh:

Manual lever 32 is fulcrumed at 33 to the carriage framing and the aforesaid pivotal arm 13, which is pivoted at one end thereof at 34 to said lever 32 at one side of the fulcrum 33 thereof, at the other end and on the other side of said fulcrum 33 has fast connection to be explained with the aforesaid shaft 8 whereon spur gear 5 is mounted, operation of manual lever 32 therefore allowing fractional rotation of shaft 8 and gear 5, under the influence of spring 11'.

Manual lever 14 operable as described to accomplish bodily movement of the gear 5, is provided with a spring 35 acting to hold said lever in either of its two adjusted positions, that is to say with gear 5 moved into mesh with platen gear 6 or away therefrom, said lever engaging stop 36 of the carriage framing to limit its outward movement and engaging lever 32 to limit its inward movement.

In adjusting the signal into operative engagement, the operator pulls forward on manual lever 14, and, in order to make the routine the same under all conditions, having given lever 14 a slight lead, will exert pressure upon manual lever 32; continuing pressure upon both levers until the gears 5 and 6 come into mesh.

In case fractional adjustment of the parts occurs, a lug 37 of lever 14 is adapted to engage over a projection 38 of lever 32 to hold the latter against retraction under influence of its spring 39; whereas, if no fractional adjustment occurs, lug 37 will move under projection 38, and prevent movement of lever 32. The handle arm of lever 32 and extension 32' of said lever are adapted to engage opposite sides of carriage frame stop 40, to limit its movement in both directions.

The spring 11 is a spirally coiled spring and fits over a reduced outer end portion of shaft 8 with in an outer end recess sleeve 7, a screw 8' engaging the outer end of said shaft having a head bearing against the outer end of the spring. The spring 11' is a helically coiled spring and fits within an inner recess of the hub portion of gear 5, with one end fast to the gear and the other end fast to the shaft, said spring exerting tension against gear 5, to normally hold lug 28 thereof against stop lever 29, rotation of said gear dur-

ing the typing of matter on the paper sheet being against the tension of said spring.

In assembling the parts, the gear 5 with spring 11 in place is fitted over the enlarged inner end portion of shaft 8 to contact collar 8'' of said shaft; spring 11' is fitted over the reduced outer end portion of shaft 8 and screw 8' engaged with shaft 8 to confine spring 11'; sleeve 7 has the enlarged inner end portion of its bore rotatably engaged over collar 8'' and the outwardly extending hub portion of gear 5, the inner terminal threaded stem of shaft 8 being then engaged with a perforation of the outer end of pivotal arm 13, and finally clamp nut 41 is engaged with said stem to make shaft 8 fast to pivotal arm 13 and hold the parts together. The manual lever 14 has the cam slot thereof engaged with a reduced portion of said clamp nut 41, which forms in effect an extension of shaft 8.

The signaling mechanism is useful to give notice when the last of a predetermined number of lines of matter being typed upon the paper sheet is reached, for instance; first, when the sheet is full; second when a number of columns of matter of even length are being typed on the sheet and the end of one column is reached, or third when it is desired to take a total or sub-total following the typing of each given number of lines in a column.

In the first case, the paper sheet is withdrawn 30 and a new sheet inserted; in the second case, the platen is reversely rotated by use of the main handle knob until lateral stud 28 of gear 5 has stop engagement with lever 29, the typing of the next column being then started, and in the third case, the total being taken, manual lever 14 is operated to disengage gear 5 from pinion 6, whereupon the gear 5, sleeve 7 and radial arm 9 will be reversely rotated as a unit by spring 11' to first or starting position, lateral stud 28 of 40 said gear having stop engagement with lever 29 to limit the movement.

I claim:

1. In a listing machine, a shiftable carriage provided with a rotary platen, line spacing and fractional line spacing means for the platen, signaling means for the last item of a column of matter to be typed upon a paper sheet passing around the platen including a signal gear, the platen shaft having a gear with which the signal gear is adapted to mesh, and means for accomplishing meshing of the gears following fractional line spacing rotation of the platen including conjointly manually operable devices for moving said signal gear bodily relative to the platen gear and for simultaneously fractionally rotating the signal gear and for gaging the fractional rotation, said manually operable devices including each a lever, the two levers having adjacent handle arms operable by simultaneous pressure.

2. In a listing machine, a shiftable carriage provided with a rotary platen, line spacing and fractional line spacing means for the platen, signaling means for the last item of a column of matter to be typed upon a paper sheet passing around the platen including a signal gear having a shaft, the platen shaft having a gear with which the signal gear is adapted to mesh, and means for accomplishing meshing of the gears following fractional line spacing rotation of the platen including conjointly manually operable devices for moving said signal gear bodily relative to the platen gear and for simultaneously fractionally rotating the signal gear and for gaging the fractional rotation, the manually opera-

ble devices including each a lever having a fulcrum on the carriage, the lever of one of said manually operable devices being provided with an arm pivoted thereto and having fast connection with the shaft of the signal gear and whereon the signal gear is mounted.

3. In a listing machine, a shiftable carriage provided with a rotary platen, line spacing and fractional line spacing means for the platen, signaling means for the last item of a column of matter to be typed upon a paper sheet passing around the platen including a signal gear, the platen shaft having a gear with which the signal gear is adapted to mesh, and means for accomplishing meshing of the gears following fractional line spacing rotation of the platen including conjointly manually operable devices for moving said signal gear bodily relative to the platen gear and for simultaneously fractionally rotating the signal gear and for gaging the fractional rotation, the manually operable devices including each a lever having a spring to hold the lever in operated position and the levers having interlocking means adapted to hold the other lever in operated position.

4. In a listing machine, a shiftable carriage provided with a rotary platen, line spacing and fractional line spacing means for the platen, signaling means for the last item of a column of matter to be typed upon a paper sheet passing around the platen including a signal gear having a shaft, the platen shaft having a gear with which the signal gear is adapted to mesh, and means for accomplishing meshing of the gears following fractional line spacing rotation of the platen including conjointly manually operable devices for moving said signal gear bodily relative to the platen gear and for simultaneously fractionally rotating the signal gear and for gaging the fractional rotation, the manually operable devices including each a lever having a fulcrum on the carriage, the lever of one of said manually operable devices being provided with an arm pivoted at one end thereto at one side of its fulcrum, said arm at its other end and at the other side of said fulcrum having fast connection with the signal gear shaft.

HOWARD MOFFATT FLEMING. 28
